UNITED STATES PATENT OFFICE.

EDWIN F. GUTH, OF ST. LOUIS, MISSOURI.

LIGHTING FIXTURE.

Application filed July 5, 1921. Serial No. 482,355.

My invention relates to the art of illumination and has for its object to produce an efficient and practical enclosed lighting unit, adapted for controlling and varying 5 the distribution and diffusion of the light rays within a certain determined radius on the working plane.

A further object is to produce such a device in a simple and easily operated construction so that any user, although unskilled in the art, may adjust the reflector of my unit to secure the exact distribution he desired. In other words, my improved lighting fixture is a unitary structure ready for installation in any place, and the ordinary user can adjust it to produce the exact lighting effect he may desire.

My invention consists of the arrangement and correlation of parts, as illustrated, described and claimed. In the drawing the figure shows a view, largely in section, of my improved lighting unit.

Referring to the accompanying drawings the reference numeral 10 is used to indicate 25 the light source, or lamp, 11 the socket, 12 the shell surrounding the socket, 13 the bowl holder, which is secured to the shell, and 14 the bowl which surrounds the light source and is removably secured to the bowl holder. 30 A reflector 15, preferably of the conformation shown in the drawing, surrounds the light source, and is adjustably held in position by rods 16, or the like, extending upwardly therefrom and seated in the bowl holder. These rods are preferably screw threaded on one end and seated, in rotating 35 mountings secured in the bowl holder. This means of adjustably securing the reflector may be varied without altering my invention, as the only material function of this part is to cause the reflector to be so mounted that it may easily and quickly be adjusted by moving it up or down, at the desire of the user.

40 My reflector is a very important element of my invention and is constructed with a

narrow opening at the top, very little wider than the neck of the lamp to be used, and extends downwardly around the enlarged portion of the lamp and flares outwardly to a 50 limited extent, the preferable shape and construction being as shown in the drawing.

It is my purpose to have this reflector placed so that normally it will intercept all light rays above a 50 degree angle from the 55 perpendicular though, of course, this can be, and will often be, varied at the desire of the user, for it is obvious the raising or lowering of the reflector will enlarge or diminish, as the case may be, the degree of light rays 60 which will impinge thereon and cause the reflector to function to concentrate or more widely diffuse the light as desired.

The reflector surrounding the lamp is of sufficient depth to intercept all direct rays 65 of light at an angle considerably below the horizontal line. This makes it practical for me to use a very light density of glass in the bowl, and tests of my unit, so constructed, performed to the highest degree in the efficiency of inclosed units.

Having thus described my invention, what I claim and desire to secure by Letters Patent of the United States, is:

1. A lighting fixture comprising a canopy, 75 a light source and inclosing bowl and a reflector within the bowl, said reflector having an opening in its top slightly larger than the neck of the light source and extending downwardly below the light source and flaring outwardly so as to surround the light source; said reflector being also mounted for vertical adjustment from the canopy of the fixture.

2. A lighting fixture comprising a light 85 source and an enclosing bowl and a reflector within the bowl, said reflector surrounding the light source and depending below the same, and being also adjustably secured to the fixture canopy, substantially as shown 90 and described.

EDWIN F. GUTH.
